(57) **CLAIM**

The ornamental design for the bubble level, as shown and described.

DESCRIPTION

FIG. 1 is an isometric view of the bubble level;
FIG. 2 is a front elevational view of the bubble level;
FIG. 3 is a back elevational view of the bubble level;
FIG. 4 is a left side elevational view of the bubble level;
FIG. 5 is a right side elevational view of the bubble level;
FIG. 6 is a top plan view of the bubble level; and,
FIG. 7 is a bottom plan view of the bubble level.
It is understood that the dashed lines presented in the drawings are for illustration only, and do not form a part of the claimed design.
